UNITED STATES PATENT OFFICE.

CHARLES PETER MITCHELL JACK, OF GLASGOW, SCOTLAND.

NAVIGABLE VESSEL.

1,393,537.

Specification of Letters Patent.

Patented Oct. 11, 1921.

Application filed February 16, 1921. Serial No. 445,497.

To all whom it may concern:

Be it known that I, CHARLES PETER MITCHELL JACK, a subject of the King of England, residing at Glasgow, Scotland, 5 have invented certain new and useful Improvements in Navigable Vessels, of which the following is a specification.

This invention is for improvements in or relating to navigable vessels designed for 10 carrying liquids in bulk, such for example as oil.

Navigable vessels for carrying liquids in bulk have been designed in which there are vertical tanks forming part of the structure 15 of the vessel and in order to obtain the maximum carrying capacity these tanks have been of rectangular form extending from side to side of the vessel. The capacity of any such rectangular tank cannot exceed 20 certain safe limits and, it has been found, for this reason, necessary to employ a center-line bulkhead which separates the tanks into two rows one on each side of the bulkhead. A vessel so constructed depends for 25 its buoyancy on compartments at the bow and the stern of the vessel, but it is found desirable, in order to give transverse stability, to have in addition to the bow and stern compartments, unfilled buoyancy compartments along the sides of the vessel. 30

Such compartments for giving lateral stability have been provided hitherto, according to one construction, by forming the vertical tanks by approximately semi-circular bulkheads directly connected to the sides of the hull, the tank proper being constituted between opposed concave faces of adjacent bulkheads. Inter-tank spaces between the convex sides of adjacent bulkheads would normally constitute the lateral 40 stability compartments.

An advantage of the cylindrical tanks is that, by the natural strength which is consequent on its form, each such tank replaces 45 four of the rectangular tanks and eliminates considerable weight of metal, for example that comprising two of the sides of each of the rectangular tanks. Moreover, there are fewer tanks to test and to main- 50 tain.

The present invention is applied to a ship of the type in which the hold space is divided into tanks with their angles filled by plating in large circular curves, which 55 curves may, if desired be all struck from one center.

The object of this invention is to construct for oil-carrying vessels, tanks of such form that the advantages as to strength and stiffness of a circular tank are substantially 60 retained, and that the strength of the tank shall be sufficient within its own structure to take up without aid from the hull structure, all the stresses due to the pressure of the tank contents; consequently, the hull 65 structure is not stressed by supporting the bulkhead stresses which have heretofore come upon it, and have resulted in serious leakage.

There is a known construction of ship 70 wherein the divisions between the hull spaces consist of bulkheads, the middle of the width of each bulkhead extending across only a portion of the width of the ship and being common to the spaces which 75 are at the forward and after faces of it and in which bulkhead at and divergent from each of the vertical ends of this portion of the width of the bulkhead are a pair of wings concave to the interior space of 80 adjoining tanks and extending toward the hull so as to leave between the hull and the wings stability compartments which are vertical and are separate from the aforesaid tank spaces. The construction, accessibility 85 of the joints and maintenance of these compartments and the adjoining parts of the ship's structure are improved according to the present invention by the employment of vertical web-plate distance- 90 pieces which are wider than the frames and constitute short bulkheads and are used as distance pieces to connect and at the same time to keep apart the end of each wing and the adjacent part of the bulkhead or 95 ship's skin, so that the outer ends and inner ends of the wings are liquid-tight in the ship and so that in the neighborhood of these ends ample space is afforded for the use of riveting and calking tools upon them 100 and on adjacent parts of the ship's structure during construction, and for painting and inspection and repair subsequently.

As the continuity of the plating of the wings is interrupted where the aforesaid 105 vertical web-plate distance-pieces are situated, the structural strength of the tank, regarding said tank as a unit, is according to the present invention, maintained throughout its circumference by the combination with the aforesaid vertical web-plate 110 distance-pieces, of brackets extending from

one margin of each web-plate in continuation of the line of the wings and being connected with thwartship and longitudinal ties, each wing being thus connected with 5 the next adjacent wing in the same tank by these brackets and ties or stringers, for in addition to the stringers being connected to the web-plates by way of the brackets, the ends of the stringers are themselves at- 10 tached to the web-plates.

One preferred form of the invention will now be described in detail by way of example with the aid of the accompanying drawings in which—

15 Fig. 1 is a part vertical section on the center line of a portion of the vessel embodying the present improvements;

Fig. 2 is a section on the line II—II of Fig. 1; and

20 Fig. 3 is a section on the line III—III of Fig. 2.

Like reference numerals indicate like parts in the figures.

The hull of the vessel is indicated generally by the reference numeral 1 and, as is customary with such vessels, a double bottom is provided between the outer skin 2 and inner bottom plating 3.

25 The ship is divided into tanks 20 by transverse vertical bulkheads, the middle portion 4 of each of which is flat and extends partly across the ship and is common to two adjacent tanks.

30 At the side margin of each bulkhead 4 is a pair of wings 5, 6, each wing concave to the interior spaces of the adjoining tanks 20, and extending from the central portion of the bulkhead toward the skin of the vessel. In combination with each wing in a 35 pair (take for instance one wing 5) is one of the vertical web-plates 7 that is substantially wider than the vessel's frames and that might be so wide as to constitute a short bulkhead and is appropriated to that wing 40 and forms a distance-piece connecting but keeping apart the ship's skin and the outer end of the wing, and thus leaving space between the skin and wing in which work can 45 be done. The two web-plates 7 of a pair of wings 5 and 6 at one side of a tank have 50 their outboard margins tied to one another by stringers 10. A vertical web-plate 7 (similar to the web-plates 7) connects but keeps apart the inner end of the wing 6 and 55 the central part of the bulkhead 4 at the place at which the adjacent wing 5 is nearest to the wing 6; thus the inner ends of a pair of wings 5 and 6 are kept apart and a working-space is afforded between them at those 60 ends.

65 Thwartship tie-beams 8 stiffen the part 4 and tie together the web-plates 7 of opposite pairs of wings, and thus anchor the ends of the curved surfaces 6, continuing the strength of opposite pairs of wings across

the space between them. Bracket-plates 11 and 9 in virtual or actual continuation of the curve of the wings 5, 6 where this is terminated by the web-plates 7 and 7^a connect the margins of those web-plates to stringers 10 70 and the thwartship ties 8. If desired the curve of the wings 6 from opposite sides of a tank can be continued across the middle of the ship so that the opposite wings unite.

The bottom of each main tank can be in 75 communication, if desired, with the space that is below it in the double bottom of the ship.

The object of the invention is achieved by the construction described as it will be seen 80 that the tanks still retain advantages of strength and lightness comparable to those which cylindrical tanks would have given.

The part 4 of the bulkheads could be 85 curved or corrugated and not necessarily flat as shown. Further, each bulkhead could be carried down, as shown in dotted lines in Fig. 1 at 14, to the plating of outer bottom 2.

What I claim as my invention and desire 90 to secure by Letters Patent is:—

1. A tank ship having tanks comprising in combination bulkheads each end of which extends toward the side of the ship in a pair of curved wings diverging away from one another and thereby forming with the sides 95 of the vessel a chamber, a vertical web-plate (such as 7) for joining each wing to the side of the vessel, another vertical web-plate (such as 7^a) for attaching the inner ends of each pair of curved wings to one another, the said web-plates being of such width and so disposed that access is readily afforded in the aforesaid chamber to the joints of the web-plates, brackets (such as 11 or 9) 100 each attached at one end to an edge of a wing adjoining a web-plate and forming a virtual continuation of the wing to which it is attached, and stringers (such as 10 or 8) which tie the other end of each bracket to an opposed end of another bracket directed 105 toward it.

2. A tank ship having tanks formed by bulk-heads each end of which extends toward the side of the ship in a pair of curved wings diverging away from one another and thereby forming with the sides of the vessel a chamber, and a vertical web-plate (such as 7) for joining each wing to the side of the vessel, the web-plate being of such width and so disposed in relation to the side of the 115 vessel that access is readily afforded in the aforesaid chamber to the joints of the web-plate.

3. A tank ship having tanks formed by bulk-heads each end of which extends toward the side of the ship in a pair of curved wings diverging away from one another and thereby forming with the sides of the vessel a chamber, and a web-plate (such as 7^a) 125 which attaches to one another the inner ends 130

of a pair of curved wings, the said web-plates being of such width and so disposed that access is readily afforded in the aforesaid chamber to the joints of the web-plate.

- 5 4. A tank ship having tanks formed by bulk-heads each end of which extends toward the side of the ship in a pair of curved wings diverging away from one another and thereby forming with the sides of the vessel, 45
 10 a chamber, a vertical web-plate (such as 7) joining each wing to the side of the vessel, the web-plate being of such width and so disposed in relation to the side of the vessel that access is readily afforded in the aforesaid 50
 15 chamber to the joints of the web-plate, brackets (such as 11 or 9) each attached at one end to an edge of a wing adjoining a web-plate aforesaid and forming a virtual continuation of the wing to which it is attached, and longitudinal stringers (such as 55
 20 10) which tie the other end of each bracket to an opposed end of another bracket directed toward it.
5. A tank ship having tanks formed by bulk-heads each end of which extends toward the sides of the ship in a pair of curved wings diverging away from one another and thereby forming with the sides of the vessel, 60
 25 a chamber, a vertical web-plate (such as 7^a) attaching to one another the inner ends of 65
 30 a pair of curved wings said web-plate being of such width and so disposed that access is readily afforded in the aforesaid chamber to the joints of the web-plates, brackets (such as 11 and 9) each attached at one end 70
 35 to an edge of a wing adjoining the web-plate and forming a virtual continuation of the wing to which it is attached, and stringers (such as 10 or 8) which tie the other end 75
 40 of each bracket to an opposed end of another bracket directed toward it.

6. A tank ship having tanks formed by bulk-heads each end of which extends toward the sides of the ship in a pair of curved wings diverging away from one another and thereby forming with the sides of the vessel 45
 a chamber, a vertical web-plate joining each wing to the side of the vessel the said web-plate being of such width and so disposed in relation to the side of the vessel that access is readily afforded in the aforesaid 50
 chamber to the joints of the web-plate, brackets (such as 11) each attached at one end to an edge of a wing adjoining a web-plate aforesaid and forming a virtual continuation of the wing to which it is attached, and longitudinal stringers (such as 55
 10) which tie the other end of each bracket to an opposed end of another bracket directed toward it.

7. A tank ship having tanks formed by bulk-heads each end of which extends toward the sides of the ship in a pair of curved wings diverging away from one another and thereby forming with the sides of the vessel, 60
 a chamber, a vertical web-plate attaching 65
 to one another the inner ends of a pair of curved wings, the said web-plate being of such width and so disposed that access is readily afforded in the aforesaid chamber to the joints of the web-plate, brackets (such 70
 as 9) each attached at one end to an edge of a wing adjoining the web-plate aforesaid and forming a virtual continuation of the wing to which it is attached, and thwartship stringers (such as 8) which tie the other 75
 ends of each bracket to an opposed end of another bracket directed toward it.

In testimony whereof I affix my signature.

CHARLES PETER MITCHELL JACK.
